FOREIGN PATENT DOCUMENTS

GB 2225808 6/1990

Primary Examiner—T. Chase Nelson

(74) *Attorney, Agent, or Firm*—Dowell & Dowell, P.C.

(57) **CLAIM**

The ornamental design for a gate hinge, as shown and described.

DESCRIPTION

FIG. 1 is a front perspective view of a gate hinge showing my new design;

FIG. 2 is a rear perspective view;

FIG. 3 is a left side view;

FIG. 4 is a front elevation view;

FIG. 5 is a right side view;

FIG. 6 rear elevation view;

FIG. 7 is a top plan view; and,

FIG. 8 is a bottom plan view.

The broken line showing environmental structure is for illustrative purposes only and forms no part of the claimed design.
